UNITED STATES PATENT OFFICE.

ELI HENSLEY, OF SAND SPRINGS, OKLAHOMA.

AUTOMOBILE-BOAT.

1,100,238.

Specification of Letters Patent. Patented June 16, 1914.

Application filed November 25, 1913. Serial No. 802,876.

To all whom it may concern:

Be it known that I, ELI HENSLEY, a citizen of the United States, residing at Sand Springs, in the county of Tulsa and State of Oklahoma, have invented certain new and useful Improvements in Automobile-Boats, of which the following is a specification.

This invention relates to power boats and the primary object is to provide a boat of very light draft that will operate satisfactorily on streams where the water is shallow, or where sand bars and the like are apt to be encountered. To this end the invention contemplates the provision of a flat bottomed body or hull having at each end thereof a propeller wheel of special design, such wheels being capable of travel over land as well as water. Rudders are provided at both ends of the boat and are arranged to be swung simultaneously in opposite directions so as to enable short turns to be made.

In order that the invention may be readily understood, reference is had to the accompanying drawings, forming a part of this specification, and in which,

Figure 1 is a side elevation of the complete boat; Fig. 2 is a vertical longitudinal section substantially on the line 2—2 of Fig. 3; Fig. 3 is a plan view of the boat shown in Fig. 1; Fig. 4 is a cross section on the line 4—4 of Fig. 3; Fig. 5 is a horizontal fragmentary section through the central portion of the body or hull; and, Fig. 6 is a perspective view of one of the specially constructed propeller wheels.

Referring to the drawings in detail, the frame of my improved boat is formed of two side members 1 and 2, preferably in the form of angle bars. The extreme ends 1^a and 1^b and 2^a and 2^b of these side members are brought together to form a wedged configuration at both the stern and bow. The hull or body designated at 3 is located between the central portion of the side members, and has a bottom either flat or slightly rounded. In this body are located suitable seats 4, steering wheel 5, mounted on a steering post 5^a, and engine box 6 located immediately behind the seat. This engine box is preferably provided with a hinged cover 6^a, which may be swung open to afford access to the engine. This may be done from the seat. Immediately behind the engine box is a compartment 7, which may be formed air tight so as to contribute buoy-

ancy to support the weight of the engine, while a similar compartment 8 is located at the front part of the body.

At the front and rear ends of the body 60 beyond the compartments 7 and 8 are arranged hoods 9 and 10 in which are located the propeller wheels 11 and 12, mounted on horizontal transverse shafts 13 and 14, respectively. Each of these propeller wheels 65 is similar in construction and a description of one will suffice for both. Referring to Fig. 6, it will be seen that the wheel 12 comprises a central cylindrical drum 12^a, from which project a plurality of radially extending blades 12^b. These blades may conveniently be held by means of spiders 12^c having grooved arms into which the ends of the blades fit. At the center of the wheel the spaces between the blades are filled in 70 with a solid rim 12^d, over which a suitable band or tire 12^e may be placed. It will be apparent that this central rim and tire form a smooth tread adapted to roll upon the ground and thus support and propel the 75 body, when a sand bank or the like is encountered.

Mounted upon each end of the shaft 13 is a sprocket wheel 15, and mounted upon each end of the shaft 14 is a sprocket wheel 16. 85 Sprocket chains 17 and 18, respectively, extend on each side of the body from the wheels 15 and 16 to wheels 19 and 20, secured to the projecting ends of a power shaft 21 which extends transversely of the 90 body at about the center thereof. Guards 22, preferably formed of sheet metal, may be arranged over these chains and wheels if desired.

Located in the engine box 6 is an engine 95 23, which may be of any suitable type, but which is shown as a two-cylinder gasoline motor. From a sprocket wheel 24 mounted on the engine shaft extends a drive chain 25 to a sprocket wheel 26 secured to one member 27 of a clutch loosely mounted upon the shaft 21, the other member 28 of which is keyed to said shaft but capable of sliding thereon. The clutch may be controlled by any suitable lever, such as 29. 105 Other transmission mechanism between the engine and power shaft 21 may, of course, be employed without departing from the invention.

Mounted at the wedge-shaped front end 110 of the frame is a rudder 30, and mounted at the rear end of the frame is a similar

rudder 31. To the post of rudder 30 is secured a pulley 32, and to the post of rudder 31 is secured a pulley 33, and around these pulleys pass cables 34 and 35, respectively. 5 The ends of these cables are carried into the chamber 8, where they are wound around suitable drums 36 and 37 geared in any desired manner to the steering post 5^a. The arrangement of these cables and drums is 10 such that when the steering wheel 5 is turned, the rudders 30 and 31 are swung in opposite directions so as to exert a very effective turning moment upon the boat.

It will be particularly observed that the 15 lower edges of the drums 11^a and 12^a are substantially in the same horizontal plane as the bottom of the body 3, and as these drums are air tight and buoyant, it will be apparent that they assist in supporting the 20 weight of the boat. In other words, the load is carried by three separate buoyant compartments, consisting of the body and the two cylindrical drums, and owing to their location in the same horizontal plane, 25 each exerts a lifting action proportional to its displacement.

It will thus be seen that I have provided a convenient and simple motor boat which is capable of traveling at considerable speed 30 over shallow water and marshes impassable to a boat of ordinary construction, and it is thought that the many advantages of the

invention will be readily appreciated without further discussion.

What I claim is:

1. In a device of the class described, a body or hull, a transversely disposed propeller drum mounted at each end of said body, a pair of side members extending beyond the body and drums, and having their ends brought together to form a wedge-shaped frame both in front and behind said body, a rudder mounted at the point of each such frame in front of one drum, and behind the other, and means for simultaneously 40 swinging said rudders in opposite directions. 45

2. In a device of the class described, a pair of side members forming an elongated frame, wedge-shaped at each end, a body carried by said frame centrally thereof, propeller wheels journaled in said frame one in front and one behind said body, each of such wheels comprising a drum and a plurality of blades radiating therefrom, a hood 50 extending over each wheel, and a rudder mounted at each wedge-shaped end of said frame beyond the propeller wheels. 55

In testimony whereof I have affixed my signature in presence of two witnesses.

ELI HENSLEY.
